ELECTRIC STOP MECHANISM FOR
KNITTING MACHINES

Jacob Wachsman, Brooklyn, N. Y.

Application October 31, 1939, Serial No. 302,078

1 Claim. (Cl. 192—127)

This invention relates to improvements in electric stop mechanisms for knitting machines of the type disclosed in my U. S. Patent 1,845,455, February 16, 1932.

5 The object of the invention is to provide an improved type of electric stop mechanism for actuating the stop handle of the driving unit of the machine when a thread breaks or the thread runs out. More particularly it is an object of 10 the invention to provide a small compact stop mechanism having but few parts, easy of manufacture and installation and inexpensive.

With these objects in view the invention is embodied in an electric stop mechanism arranged 15 and constructed as hereinafter set forth and as illustrated in the accompanying drawing in which

Fig. 1 is a front view of the stop mechanism with the front cover removed to show the mechanism and parts are broken away.

20 Fig. 2 is an end view looking from the left in Fig. 1.

Fig. 3 is a rear view of the stop mechanism with the back cover removed and parts broken away.

25 Fig. 4 is a sectional view on the line 4—4 of Fig. 3.

Fig. 5 is a wiring diagram.

Referring first to Fig. 5 the numeral 10 indicates conventionally a stop handle of a driving unit in a knitting machine. When the handle is 30 swung on its pivot 11 the knitting machine stops. The operation is similar to that of shifting a belt pulley in other machinery. In knitting machines the operation of the stop handle is controlled by the thread. That is, when the thread breaks or 35 runs out the handle 10 is to be operated to stop the machine. The controlling mechanism is in the form of a switch which is normally held in circuit open position by the thread. Such switches are called end detectors or knot detectors or stop motions in the art. In Fig. 5 it will 40 be seen that the thread 12 runs over two guides 13, 13 and that a detector 14 rests upon the thread. The detector 14 is merely a switch arm which, when not supported by the thread, moves 45 down by any suitable means and contacts a switch plate 15 which is grounded. The detector is connected to a battery 16. This in turn is connected to an electromagnet 17. The other end of the coil is connected to a spring contact 18 which is grounded. It will therefore be seen that 50 so long as the switch or detector 14 is supported by the thread the circuit is open and the electromagnet cannot attract its armature lever 19. The latter acts to hold a plunger 20 in a set position 55 against the tension of a plunger spring 21. The

plunger is adapted to move the stop handle 10 as shown. If now the detector switch 14 closes because the thread breaks or runs out, the circuit is closed, the electromagnet is energized, the armature lever 19 is actuated to release the 5 plunger 20, the latter operated by the spring 21 in turn throws the stop handle 10 to stop the machine and the circuit is immediately open by the upward movement of the spring contact 13. Thus only for a moment is the circuit closed. 10 This is of course an advantage as it eliminates accidents due to shocks from the current. The detector switch 14 and the relation of the lever 19 and plunger 20 are shown wholly conventionally. The foregoing is a brief description of the 15 operation of a typical electric stop mechanism for knitting machines. This invention is concerned with the construction and arrangement of those parts of the mechanism whereby the plunger is held, operated and again set for the next operation.

Referring now to the other figures the plunger 20 is slidably supported in a box 22. The latter is open at the front and at the back as a matter 20 of convenience for assembling the parts. The front is closed by a front cover 23. The back is closed by a back plate 24. The box 22 supports the electromagnet 17 and the armature lever 19 is pivoted in the box at 25. A small spring 26 tends to keep the lever 19 open with respect to 30 the magnet. The lever has a small stop 27 which spaces the lever in open position with respect to the magnet as will be understood. One end of the magnet coil is connected outside the box to a circuit terminal 28 of well known design. The other end of the magnet coil is connected to the contact spring 18. The armature lever 19 has a small stop lip 29 which by the action of the said small spring 26 is held in position in front of and in engagement with the tail end 30 of a plunger 40 holding lever 31 which is pivoted at 32 and provided with a slot 33. The latter is engaged by a pin 34 which is carried by a setting lever 35 pivoted at 36. The setting lever has cam surfaces 37, 38 and two stops 39 and 40. The plunger 20 has a heavy transverse finger 41.

The operation is as follows. In setting the mechanism for action the operator pushes the plunger to the right in Fig. 3 against the tension of the spring 21, the finger 41 passing over the 50 cams 37 and 38 and against the stop 39 thereby moving the setting lever 35 clockwise about its pivot 36 so that the pin 34 by engagement with the slot 33 in the locking lever 31 moves the latter anticlockwise about the pivot 32 whereby to bring 55

the tail 30 of lever 31 down behind and in engagement with the stop lip 29 of the armature lever 19 which thus holds the locking lever 31 against movement until the magnet is energized.

5 This action is evidenced by a clicking noise. The operator then lets go of the plunger which then by the spring 21 is pushed backwards until the finger 41 rests against the other stop 40 on the setting lever 35. The mechanism is now set and 10 ready for operation. The plunger spring is compressed between the finger 41 and the wall of the box and the finger has also engaged and depressed the spring contact 18 to ground against the box itself.

15 In this normal position of the parts there is a steady pressure by the plunger spring 21 upon the finger 41 and the plunger 20 to push the plunger in the opposite direction, to the left in Fig. 3. Such movement cannot however, take 20 place until the locking lever is released, said lever preventing movement of the pin 34 and setting lever 35. When the plunger is set by the operator it is of course also brought into suitable operative connection with the stop handle 10 depending upon the particular location and construction thereof.

When now the circuit is closed at the detector switch as described in connection with Fig. 5, the magnet is energized, the armature lever is 30 retracted, the stop lip 29 moves away from the tail 30 of the locking lever and the latter is released. Now, by the force of the plunger spring 21, the plunger is pushed quickly to the left in Fig. 3 and the stop handle 10 is actuated to stop the machine.

35 When the plunger is thus moved it swings the setting lever 35 anticlockwise about the pivot 36, the pin 34 moving upwards in the slot 33 to swing the locking lever clockwise about the pivot 32. The blow of the plunger as it is operated by the plunger spring is cushioned by a cushion spring 42. Also as soon as the finger 41 moves away from the spring 18 the latter tips upward and breaks the circuit as explained above. The 40 armature lever 19 is then moved away from the magnet by the spring 26 a distance measured by the small stop 27 and whereby the stop lip 29 is positioned to permit the tail 30 to pass behind the same.

45 To sum up: The electric stop mechanism is set by the operator to compress the plunger actuating spring 21 and at the same time cause the locking lever tail 30 to be caught behind and held by the armature lever stop lip 29. The circuit is also grounded. When the circuit is closed at the detector switch 14 the magnet is energized, the locking lever 31 released and the plunger spring quickly and rather forcibly actuates the plunger to operate the driving unit stop handle 10.

50 When the plunger is actuated by the spring the finger 41 snaps over the corner of the stop 40 and thus rides over the cam surface 38 to push down the setting lever on the one side of the pivot 36. This brings the other cam surface 37 down into an inclined position to be engaged by the finger 41 when the mechanism is set by

the operator so that the finger 41 glides easily in over the setting lever and into engagement with the stop 39 to move the pin 34 downward in the slot 33 to reset the locking lever.

5 The plunger 20 may have a convenient handle as at 45 in Fig. 5. In order to test the mechanism apart from the operation of the detector switches a small pin 46 is provided which is accessible from the outside for the purpose of tripping the armature lever 19, see Figs. 1 and 4. 10 After the mechanism has been set the operator may push the pin inward to trip the lever 29 whereupon the plunger will be actuated and the operator will know that the mechanism is in order. The magnet is attached to the box by a 15 screw 50. In order to prevent accidental or wilful loosening of this screw the cover 23, Fig. 2, is provided with a bent lip 52 which conceals the screw.

20 The stop mechanism according to this invention is characterized by extreme simplicity in construction and comprises relatively few parts. It is easy to manufacture and assemble and extremely efficient in operation. The box may be mounted in any convenient position to engage 25 the stop handle 10 and the plunger is readily shaped for such engagement.

I claim:

30 In an electric stop mechanism for power driven machines wherein is provided an electric circuit with a normally open circuit closer controlled by the material being operated upon and which includes a stop handle; a plunger for actuating said stop handle, a finger on said plunger, a spring for moving the plunger in one direction, 35 a setting lever, two stops thereon, one of said stops engaging said plunger finger to hold the plunger immovable against the action of said spring, a locking lever in operative engagement with said setting lever to maintain said stop 40 thereon in engagement with said plunger finger, an electromagnet in said circuit, an armature for said magnet arranged to hold said locking lever in operative engagement with the setting lever and arranged to release the locking lever when the armature is attracted by the magnet, an automatic switch in said circuit embodying a 45 spring member normally tending to automatically open said circuit, said spring member being mounted in the path of movement of said plunger finger to engage said setting lever and arranged to be moved into circuit closing position by said finger during its said movement and maintained in circuit closing position by said finger thereafter, a second stop on the setting lever arranged to be momentarily engaged by said plunger finger to move said setting and locking levers into normal plunger holding positions, said plunger and finger thereon being moved by 50 said spring into engagement with said first named setting lever stop after said setting and locking levers have been moved into normal plunger holding positions as aforesaid, a box through which said plunger slides, said box enclosing and supporting all of the aforesaid elements.

55 60 65 JACOB WACHSMAN.
